UNITED STATES PATENT OFFICE.

SAMUEL C. GAULT, OF CINCINNATI, OHIO.

SKATE.

SPECIFICATION forming part of Letters Patent No. 255,161, dated March 21, 1882.

Application filed August 22, 1881. (No model.)

To all whom it may concern:

Be it known that I, SAMUEL C. GAULT, a citizen of the United States, residing at Cincinnati, Hamilton county, Ohio, have invented 5 new and useful Improvements in Skates; and I do hereby declare that the following is a full, clear, and exact description thereof, reference being had to the accompanying drawings and the letters or figures of reference marked 10 thereon.

My invention relates to improvements in the construction of skates.

The object, purpose, and scope of my invention will appear in the following description 15 and claims.

My device is illustrated as follows in the accompanying drawings:

Figure 1 is a perspective view, the foot-plate being shown by dotted lines. Fig. 2 is a vertical section on the line $\alpha\alpha$ in Fig. 1. Fig. 3 is a horizontal section on the line yy in Fig. 2. Figs. 4 and 5 show details of construction. Fig. 6 shows various forms which may be given to the bearing-edge of the runners.

25 The parts are as follows:

A is the foot-plate. B B are the posts by which the runners are attached to the foot-plate. D D are clips, riveted to the runners, by which the connection is made with the posts 30 B B by means of the pin b , passing through the hole b' in the post. C C are blocks of india-rubber interposed between the posts and the clips. E E and E E are the runners.

It will be seen that the runners of my skate 35 are like those of a bob-sled—viz., two pairs of short runners, one under the heel and the other under the ball of the foot. These runners are connected with the foot-plate by a double joint or universal joint, which, however, is limited in its movement. The hole b' , 40 through which the pin b passes, is flaring, so as to give a horizontal movement to the pin, the vertical movement of the joint being upon the pin b as a pivot. The vertical movement is limited by the elasticity of the rubber block C.

It will be seen by Figs. 1 and 5 that the vertical and horizontal movements of the joint are not strictly so, but are within a plane at an angle to the plane of the runners. The result 50 of this construction is that a pressure from the foot of the skater which is not positively ver-

tical will depress the rubber block C at one side and in a line at an angle to the plane of the runner, and hence in a direction to move the joint horizontally also, and thus turn the 55 points of the runners in another or oblique direction. The result of this is that the skater can by a change of direction of his weight guide himself over the ice.

I will here remark that the same construction may be applied to a coasting-sled, and the occupant by swaying his body can guide the sled.

I have provided the following means for regulating the elasticity of the rubber blocks: 65 Plates $c' c'$ rest upon the top of the rubber, and set-screws $c c$, passing through the lateral arms of the post, bear upon the plates. The necessary or desirable degree of tension is effected by the movement of these screws. In place of 70 the rubber C, any other form of spring which may be found sufficient may be used.

What I claim as new is—

1. In a skate, the combination, with the foot-plate A, of a pair of double runners, E E and 75 E E, connected to said plate by a universal-joint connection which has its vertical movement limited by an interposed spring, substantially as and for the purposes set forth.

2. In a skate, the combination, with the foot-plate A, of a pair of double runners connected 80 to said plate by a universal joint, which has its vertical and horizontal movements in planes inclined to the plane of said runners and has its vertical movement limited by an interposed 85 spring, substantially as shown.

3. In a skate, a joint for connecting the runners to the foot-plate, consisting of the clip D, with pin b , post B, with flared opening b' , rubber block C, plates $c' c'$, and set-screws $c c$, 90 substantially as shown.

4. A skate having a pair of runners, one under the heel and the other under the ball of the foot, and each composed of two blades lying parallel with each other.

In testimony that I claim the foregoing I have hereunto set my hand this 9th day of July, 1881.

SAMUEL C. GAULT.
